UNITED STATES PATENT OFFICE.

THOMAS J. MARCH, OF POTTSTOWN, PENNSYLVANIA.

HEATING APPARATUS.

SPECIFICATION forming part of Letters Patent No. 734,728, dated July 28, 1903.

Application filed May 31, 1902, Serial No. 109,749. (No model.)

To all whom it may concern:

Be it known that I, THOMAS J. MARCH, a resident of Pottstown, in the county of Montgomery and State of Pennsylvania, have invented certain new and useful Improvements in Heating Apparatus; and I do hereby declare the following to be a full, clear, and exact description of the invention, such as will enable others skilled in the art to which it appertains to make and use the same.

My invention relates to an improvement in heating apparatus, and more particularly to a combined hot-air and hot-water or steam furnace, the object of the invention being to utilize the otherwise waste products of combustion to heat water in a drum inclosed in the hot-air chamber of a furnace.

With this object in view the invention consists in certain novel features of construction and combinations and arrangements of parts, as will be more fully hereinafter described, and pointed out in the claims.

In the accompanying drawings, Figure 1 is a view, partly in section, illustrating my improvements. Fig. 2 is a view in longitudinal section of the heating-drum. Fig. 3 is a horizontal section of the same, and Figs. 4 and 5 are views of the baffle-plate 9.

1 represents an ordinary hot-air furnace inclosed in a casing 2, forming an air-heating chamber all around the furnace, and 3 represents my improved hot-water heating-drum, inclosed in casing 2 and connected with the smoke-outlet of furnace 1 at its upper end by suitable nipple 4 to direct the smoke and gases through the drum to heat the water, as will hereinafter appear. The drum 3 is preferably of the general shape shown, supported on suitable legs or feet 4^a and provided near its lower end with a clean-out port 5, extending through casing 2 to permit the drum to be readily cleaned out when necessary. In the drum a series of vertical parallel water-tubes 6 are located, each series comprising, preferably, three tubes connected together at their upper and lower ends and forming a coil and all of the coils connected at their upper and lower ends, forming a continuous passage for the water-flow, an inlet 7 being located at the lower end of one coil at one side of the drum and projecting through the drum to be connected

with the return from the radiators and the outlet 8 being located at the upper end of the other extreme coil and projecting through the drum to be connected with the radiator supply-pipe.

A baffle-plate or deflecting-partition 9 of the shape shown in Figs. 4 and 5 is located in the drum, closing the space above the coils save for an elongated opening or port 10 and curving around the upper intermediate connections of the coils, as shown at 10^a, and extending down between the central vertical pipes of the coils in the form of the teeth of a comb, thus closing the space between the coils as far down as desired to compel the smoke and products of combustion to pass downward and under the baffle-plate 9 to insure the thorough heating of the coils before the smoke and gases escape through a smoke-flue 11 near the upper end of the drum and projecting through casing 2.

To the baffle-plate 9 at the lower edge of port 10 a damper 12 is hinged, the baffle-plate at the upper edge of said port being bent to form a seat 13 for said damper when closed and prevent the passage of the smoke and gases directly to the smoke-flue, thereby compelling the roundabout current of the products of combustion to heat the water in the coils. This damper is only opened when a through-draft is desired for rapidly carrying off the smoke and gases and is normally closed or partially closed during the greater period. A rod 14 is secured to the damper 12 and projects through drum 3 and casing 2 and is provided with a suitable hand-hold to permit the easy operation of the damper.

In operation the smoke and gases from the furnace pass into drum 3 through port 4, thence down and around baffle-plate 9, heating the water in the coils 8, and escapes through smoke-flue 11.

It will be seen that my improvements do not interfere in the slightest with the heating of air in casing 2 to be supplied through ordinary hot-air pipes to the rooms of the house, but in addition provide a hot-water heater to heat portions of the house as desired.

The furnace 1 is provided with a fuel-feed chute 15 and an ash-chute 16, which latter also serves as a draft-entrance. In the top of fuel-chute and about midway its ends

a plate 16^a is secured by a bolt or screw, as shown, and provided at one edge with curved fingers 16^b to enter slots in a smoke-curtain 17 and hinge the same thereon. This curtain partially closes the feed-chute to prevent any escape of smoke and gases, but swings freely, so as not to interfere with the feeding of fuel to the furnace.

On the bottom of feed-chute 15 an inverted dished plate 18 is secured and forms an air-heating chamber, with which an air-flue 19 communicates and is connected with the draft-entrance 16 to supply fresh air to this chamber. The inner end of this plate 18 is notched or serrated to break up the sheet of air and distribute it throughout the combustion-chamber over the fuel and consume all gas, the air supplied being heated by its contact with the hot plate 18.

Various slight changes and alterations might be made in the general form and arrangement of the several parts described without departing from my invention, and hence I do not limit myself to the precise construction set forth, but consider myself at liberty to make such slight changes and alterations as fairly fall within the spirit and scope of my invention.

Having fully described my invention, what I claim as new, and desire to secure by Letters Patent, is—

1. The combination with a furnace, of a drum arranged in proximity to the fire-chamber and communicating therewith, said drum having an outlet, a water-heater located within said drum, a baffle mounted on said water-heater, and a damper carried by the baffle-plate above the water-heater.

2. The combination with the fire-pot and

casing of a hot-air furnace, of a drum built 40 into the furnace structure and located in the hot-air space between the fire-pot and the casing and having means for the entrance and exit of products of combustion, a water-heater complete in itself, located in said drum, 45 and means for directing smoke and gases around and among the pipes of the water-heater.

3. The combination with a furnace having a fuel-chute and an ash-chute or draft-entrance, of a hinged smoke-curtain in the fuel-chute, a plate spaced from the bottom of said fuel-chute, and a flue connecting the draft-entrance with the fuel-chute below the plate therein.

4. The combination with a furnace having a fuel-chute and an ash-chute or draft-entrance, of a smoke-curtain hinged at its upper edge to the top of the fuel-chute, a plate spaced from the bottom of the fuel-chute to 60 form a draft-passage into the combustion-chamber on top of the fuel, and a flue connecting the draft-entrance with said passage.

5. The combination with a furnace having a feed-chute and an ash-chute or draft-entrance, of a plate spaced from the bottom of the feed-chute to form a heating-chamber and draft-passage into the combustion-chamber on top of the fuel to consume the gas, and a flue connecting the draft-entrance with said 70 passage.

In testimony whereof I have signed this specification in the presence of two subscribing witnesses.

THOMAS J. MARCH.
